United States Patent Office

Des. 182,110
Patented Feb. 18, 1958

182,110

ROLLER RULER

Jack Fairchild Fleming, Summit, N. J., assignor to Sterling
Plastics Co., Union, N. J., a corporation of New Jersey

Application July 5, 1957, Serial No. 46,854

Term of patent 14 years

(Cl. D52—1)

Fig. 1 is a top plan view of a roller ruler embodying my new design;

Fig. 2 is a front elevation thereof;

Fig. 3 is a rear elevation thereof; and

Fig. 4 is a side elevation thereof.

I claim:

The ornamental design for a roller ruler, substantially as shown.
